UNITED STATES PATENT OFFICE.

CHARLES A. DORN, OF CANTON, OHIO.

PULVERIZING MACHINE.

Application filed October 15, 1921. Serial No. 507,932.

To all whom it may concern:

Be it known that I, CHARLES A. DORN, a citizen of the United States, residing at Canton, in the county of Stark and State of Ohio, have invented certain new and useful Improvements in Pulverizing Machines, of which the following is a specification.

The invention relates to machines for pulverizing coal and the like, and the object 10 of the improvement is to supplement the direct action of rotary beaters and the wall of a horizontally positioned twin cylinder case and to pulverize the coal by a cyclonic action whereby the particles of the material 15 are powdered by impinging one another in a segmental opening between the cylinders.

The objects of the improvement are attained by the use of a case forming two parallel cylindric chambers having a longitudinal communicating cylindrical segment opening between the cylinders, each cylinder having a series of beaters rotating in the same direction creating a cyclonic action in the communicating opening, and baffle 20 flanges in the case between the beaters, and a central inlet hopper at one end of the case and centrifugal impellers drawing the pulverized material from the other end of each cylinder for discharging the same therefrom. 25

30 A preferred embodiment of the invention is illustrated in the accompanying drawings, forming part hereof, in which—

Figure 1, is a plan section of the machine in the horizontal plane of the axes of the cylinders;

Fig. 2, a longitudinal elevation section, on line II—II, Fig. 1;

Fig. 3, a transverse section on line III—III, Fig. 2; and

40 Fig. 4, a transverse section on line IV—IV, Fig. 2.

Similar numerals of reference refer to similar parts throughout the several figures of the drawings.

45 The case 1 of the machine is in the form of two elongated cylinders horizontally positioned side by side with a longitudinal opening 2, between them. A removable lining 3 of hardened metal is preferably provided 50 in the case, upon which a series of inwardly projecting annular flanges 4 are formed at spaced intervals forming the annular channels 5 between them, which flanges extend entirely around the inner face of the cylinders, excepting only at the longitudinal

opening 2 formed by intercepting segments of the cylinders, which is unobstructed.

Axial shafts 6 are mounted in each cylinder by means of bearings 6' at the ends of the case, and upon each shaft is keyed a series of hubs 7 from which project radial beater arms 8, the ends of which extend into the annular channels between the flanges 4.

The face 9 of each beater arm is slightly inclined in the direction of its width so as to deflect the material toward the rear or outlet end of the cylinder, and the length of the arms is such that they pass adjacent to, without striking the arms in the adjoining cylinder.

70 The shafts operate in the same direction by means of separate motors, so that the adjacent ends of the beaters pass each other in opposite directions on each side of the longitudinal opening 2, between the cylinders, thereby creating a cyclonic action 75 therein.

Coal or other material to be pulverized is received through a hopper 11 and a central port 12 controlled by an adjustable gate 13 in the upper part of the forward end of the machine; and the material may be fed into the hopper from a supply reservoir 14 by a screw conveyor 15 discharging upon a conveyor belt 16 delivering into the hopper 11, and the material preferably passes through a magnetic comb 17 for extracting metallic substances therefrom.

80 The rear end of the case is shaped to form chambers 18 and 18' having centrifugal fans 19 mounted on the shafts 5 therein, and each chamber having a central annular inlet opening 20 around the shaft in its rear wall and a peripheral outlet opening 21 and 21' communicating with a discharge pipe 22 leading to a consuming furnace or other place of use or storage; there being an axial port 23 in the rear wall of the case for each fan, and an adjustable damper 24 for each port.

85 An adjustment of the gate 13 controls the amount of coal and air which may enter the forward end of the machine and an adjustment of the damper 24 regulates the amount of additional air which may enter the rear side of the fan to mix with the coal dust delivered to a furnace, thereby controlling combustion therein.

90 In the operation of the machine, the material to be pulverized is fed through the

- hopper 11 and the port 12 into the forward end of the machine in the median line thereof, at the forward end of the longitudinal opening 2 between the cylinders, where it is impinged by the first set of beaters in one or the other cylinder and thrown centrifugally outward thereby into and along the first annular channel whereby it is crushed or reduced to a certain extent.
- 10 The inclined faces of the beaters urge the material rearward and some of it finds its way through the opening inside the flanges 4 into the path of the next set of beaters, wherein the centrifugal action further crushes and reduces the material.

When the material is carried around the cylinder back to the longitudinal opening between the same, the intervening currents caused by the opposite movement of the beaters on opposite sides of the opening, creates a cyclonic movement of the material which is thereby ground upon itself; which centrifugal and cyclonical actions are repeated by the successive sets of beaters until 25 the material reaches the rear end of the machine.

As fast as the material is reduced or pulverized to a fine powder it floats more or less in the air throughout the entire cavity of 30 the cylinders, and is subject to the suction created by the centrifugal fans, and is drawn through the inlets thereto at the rear ends of the cylinders, and is discharged through the pipe 22.

35 Although a considerable portion of the material is crushed by the action of the beaters and the walls of the cylinders, the greater portion of the pulverizing action is accomplished by the cyclonic action in the longitudinal segmental opening between the cylinders, thereby saving the beaters and the walls of the cylinder from the greater abrading action to which they will be subject if they did all the work of reducing the 45 material.

Furthermore the larger particles of the material are thrown into the channels between the flanges 4 and are thereby retarded so that only the smaller and lighter particles 50 move rearward in the machine and only the finely pulverized or powdered material is drawn and discharged therefrom by action of the centrifugal fan.

It is evident that the beaters in the respective cylinders may be operated at the same or at different speeds without departing from the spirit of the invention; and it has been found in practice that coal and other like materials need not be previously 60 dried for being pulverized in the improved machine.

I claim:

- 65 1. A pulverizing machine comprising a horizontal twin cylinder case having a longitudinal segmental opening between the cyl-

inders, rotating beaters in the cylinders creating a cyclonic action in the segmental opening, a material inlet means at the forward end of the case and suction means at the rear end thereof drawing and discharging pulverized material therefrom. 70

2. A pulverizing machine comprising a horizontal twin cylinder case having a longitudinal segmental opening between the cylinders, rotating beaters having rearwardly inclined faces in the cylinders creating a cyclonic action in the segmental opening, a material inlet means at the forward end of the case and suction means at the rear end thereof drawing and discharging pulverized material therefrom. 75

3. A pulverizing machine comprising a horizontal twin cylinder case having a longitudinal segmental opening between the cylinders, a series of internal annular flanges in the cylinders forming annular channels therein on each side of the opening, rotating beaters in the cylinders creating a cyclonic action in the segmental opening, a material inlet means at the forward end of the case and suction means at the rear end thereof drawing and discharging pulverized material therefrom. 85

4. A pulverizing machine comprising a horizontal twin cylinder case having a longitudinal segmental opening between the cylinders, rotating beaters in the cylinders creating a cyclonic action in the segmental opening, a gate controlled material inlet means at the forward end of the case and suction means at the rear end thereof drawing and discharging pulverized material therefrom. 90

5. A pulverizing machine comprising a horizontal twin cylinder case having a longitudinal segmental opening between the cylinders, rotating beaters in the cylinders creating a cyclonic action in the segmental opening, a material inlet means at the forward end of the case and suction means at the rear end thereof for drawing and discharging pulverized material therefrom, there being a damper controlled port in the suction means. 105

6. A pulverizing machine comprising a case forming two parallel cylinders with a longitudinal opening between them, a series of internal annular flange in the cylinders forming a series of annular channels therein on each side of the opening, beaters having rearwardly inclined faces in the cylinders rotating in the same direction for creating a cyclonic action in the longitudinal openings, said case having a material inlet opening at its forward end and suction means at the rear end thereof for drawing and discharging pulverized material. 115

7. A pulverizing machine comprising a case forming two parallel cylinders with a longitudinal opening between them, a series 120

of internal annular flanges in the cylinders case forming two parallel cylinders with a forming a series of annular channels therein longitudinal opening between them, beaters on each side of the opening, beaters having in the cylinders rotating in the same direction, for creating a cyclonic action in the rearwardly inclined faces in the cylinders longitudinal opening, said case having a 15 rotating in the same direction and extending longitudinal opening, said case having a into the annular channels for creating a material inlet opening at its forward end cyclonic action in the longitudinal opening, and separate fans at the rear end of the case said case having a material inlet opening at having inlets opening from the respective 20 its forward end and suction means at the cylinders and outlets delivering into a common discharge pipe.

10 10 rear end thereof for drawing and discharging pulverized material therefrom.

8. A pulverizing machine comprising a
